CLAIM

I claim the ornamental design for a paint bucket liner, as shown and described.

DESCRIPTION

FIG. 1 is front elevational view of a paint bucket liner showing the present invention;

FIG. 2 is a rear elevation view thereof;

FIG. 3 is a left side elevation view thereof, the right side elevation view being a mirror image;

FIG. 4 is a top plan view thereof; and,

FIG. 5 is a bottom plan view thereof.

The broken lines shown in the views define the bounds of the claimed design and form no part of the claimed design.
